(57) **CLAIM**

The ornamental design for expandable pouches combined with a belt, as shown and described.

DESCRIPTION

FIG. 1 is a front perspective view of a belt with dual expandable pouches.

FIG. 2 is a front view of dual, empty pouches according to the present invention.

FIG. 3 is a rear view of dual, empty pouches according to the present invention.

FIG. 4 is a first side view of dual, empty pouches according to the present invention;

FIG. 5 is a second side view of dual, empty pouches according to the present invention;

FIG. 6 is a top view of dual, empty pouches according to the present invention;

FIG. 7 is a bottom view of dual, empty pouches according to the present invention;

FIG. 8 is a front perspective view of dual, expanded pouches according to the present invention; and,

FIG. 9 is a rear perspective view of dual, expanded pouches according to the present invention.

The broken lines in the drawings represent unclaimed portions of the design only and form no part of the claim. The portions including surface shading represent contour and not surface ornamentation. The broken lines showing the buckles, slides, and the stitch tacks and snap hooks at either end of the zipper fastener are for illustrative purposes only and form no part of the claimed design.

The article in which the present design is embodied is a belt with two compact yet expandable pouches, each formed from a single piece of elastic fabric and having pleats in the rear. When empty, each pouch is preferably approximately the same width and thickness as the belt holding the pouches in place, and yet each pouch's width and thickness (and thus its internal volume) can expand up to 300-400% or more to hold larger items or a large number of small items.

1 Claim, 4 Drawing Sheets
